(57) **CLAIM**

The ornamental design for a table leg, as shown and described.

DESCRIPTION

FIG. 1 is a top perspective view of a table leg showing my new design;

FIG. 2 is a bottom perspective view of the design of FIG. 1 shown in an environment of use;

FIG. 3 is a top view of the design of FIG. 1;

FIG. 4 is a bottom view of the design of FIG. 1 shown in an environment of use;

FIG. 5 is a left-side view of the design of FIG. 1;

FIG. 6 is a right-side view of the design of FIG. 1 shown in an environment of use;

FIG. 7 is a front view of the design of FIG. 1; and,

FIG. 8 is a rear view of the design of FIG. 1 shown in an environment of use.

The broken lines in the drawings illustrate environment that form no part of the claimed design.
